UNITED STATES PATENT OFFICE.

PAUL NATHAN, OF NEW YORK, N. Y., ASSIGNOR TO HIMSELF AND HORATIO J. BREWER, OF SAME PLACE.

ADJUSTABLE GAGE.

SPECIFICATION forming part of Letters Patent No. 416,737, dated December 10, 1889.

Application filed August 24, 1888. Serial No. 283,659. (No model.)

To all whom it may concern:

Be it known that I, PAUL NATHAN, of the city, county, and State of New York, have invented a new and useful Improvement in Adjustable Gages, of which the following is a full, true, and exact description, reference being had to the accompanying drawings.

My invention relates to an improved gage specially adapted to machines for cutting paper or similar purposes, in which the sheets of the material to be cut are held under a clamp, and in which it is desired to cut a width narrower than the clamp from the compressed edges of said material. In these machines a gage is employed to measure the width of the strip to be cut from the compressed layers, which gage, moving upon a scale, determines the exact width so cut off; but since the edge of the material must be under the clamp the gage cannot rest under said clamp without interfering with the action of the clamp; and I therefore have devised a removable gage which can be moved beneath the clamp, and subsequently withdrawn therefrom before the clamp is depressed, thereby gaging the material to be cut, while at the same time it passes outside of the traverse of the clamp.

My invention will be readily understood from the accompanying drawings, in which—

Figure 1 represents a plan view of the adjustable part of the gage, showing the gage open; Fig. 2, an end view of the same; Fig. 3, a view corresponding to Fig. 1, showing the gage closed; Fig. 4, a vertical section through the machine, showing the clamp elevated and the gage arranged to gage the material to be cut; and Fig. 5, a plan view of the same, with part of the mechanism removed.

A represents the table upon which the gage slides and the material to be cut rests. B is the scale upon the same. The gage itself is shown at C, with the adjustable part D E attached thereto by set-screws F. The gage itself may be fed by the feeding-screw G, and the clamp H set by the screw J.

The knife K is operated by any suitable mechanism.

L represents the pile of sheets to be cut.

The adjustable gage D E is constructed on the general principle of a parallel ruler having pivoted arms M, which, by preference, have right-angled projections N, which, when

the gage is opened, as shown in Fig. 1, bear 55 against the strips O P of the gage. These strips or surfaces O P may be cut away, as shown, to allow of the passage of the arms M when the gage is closed, as shown in Fig. 3. A clip R may be employed to hold the gage 60 open, as shown in Fig. 1.

The operation of my machine can now be understood. The clamp H being raised and the gage E thrown forward to the proper point, as shown in Fig. 4, the paper L is moved up 65 against it, and the gage is then withdrawn out of the way of the clamp, which is then forced down to hold the paper in position preparatory to the cutting by the knife K. Again the gage is thrown forward and the 70 sheets fed to it. The arms M determine the fact that the gage is moved forward exactly the same distance on each occasion. It is obvious, of course, that in building new machines the main gage C may be dispensed 75 with and the adjustable gage only used; but my apparatus can be applied to existing machines in the manner shown.

What I claim as my invention, and desire to secure by Letters Patent, is—

1. The combination, in a gage for cutting-machines, of two parallel bars provided with stops, and arms pivotally secured to the bars and adapted to bear against said stops and limit the movement of said bars, substantially as described.

2. The combination, in a gage for cutting-machines, of two parallel bars, arms pivotally secured thereto, and a lock for securing said bars in position, substantially as described.

3. The adjustable gage having parts O P, arms M M, and stop-arms N N, arranged to limit the motion of the arms M M when the adjustable gage is thrown into its working position, substantially as described.

4. The combination, in a cutting-machine, of a clamp, a gage movable relatively thereto, and a parallel gage composed of two bars, one of which is secured to the movable gage and the other one is movable to and from beneath the clamp, substantially as described.

In testimony whereof I have signed my name to this specification in the presence of two subscribing witnesses.

PAUL NATHAN.
